UNITED STATES PATENT OFFICE.

HAROLD ALFRED ROGERS, OF CARDIFF, WALES.

SOUND RECORDING AND REPRODUCING MACHINE.

Application filed September 19, 1924. Serial No. 738,626.

To all whom it may concern:

Be it known that I, HAROLD ALFRED ROGERS, a subject of the King of Great Britain and Ireland, of 56 New Zealand

5 Road, Cardiff, Wales, have invented certain new and useful Improvements in or Relating to Sound Recording and Reproducing Machines, of which the following is a specification.

10 This invention consists of improvements in, or modifications of, the invention described and claimed in the specification of my earlier application Serial No. 689,744, which relates to a rolling speed control for 15 sound recording and reproducing machines adapted to run at a variable speed wherein a rolling member makes contact directly or indirectly with the needle-track and is connected by a helical drive with a governor of 20 the revolving weight type, the whole being mounted in a frame or partially enclosed in a box which is hinged horizontally and vertically to the sound box and connected by a guide rod to a pivot on the tone-arm 25 standard or casing so that the rolling member, resting on the record, directly or indirectly through an intermediate band, adapts itself to inequalities in the record surface and to angular variations with the sound 30 box maintaining its tangential alignment with each groove in the record.

According to the present invention, instead of the rolling speed control being hinged to the sound box, the guide rod to 35 which it is connected is hinged to a fixed support and connected by links to the sound arm so that the said guide rod, and consequently the rolling control, is caused to participate in the movement of the sound arm 40 across the record. The rolling speed control is similar in other respects to the control described and claimed in specification of application Serial No. 689,744.

In the preferred construction according 45 to the present invention, the connection between the tone-arm and the speed control consists of a pair of guide rods or arms pivoted at, and radiating from, a common centre at or near the tone-arm pivot, the 50 free end of one arm being attached to the speed control and the free end of the other arm to the tone-arm, the arms lying at opposite sides of the disc-record, and both of 55 said arms being connected together near their pivot by a pair of hinged links the links, being attached at the point where they

meet to a sliding block which is preferably, but not necessarily, spring controlled from the pivot of said arms or from a fixed point on the machine. In this way the traversing 60 movement of the arm connected to the tone-arm to or from the centre of the record is transmitted to, and imitated by, the arm connected to the speed control in an equal or in an unequal ratio, according to the 65 respective lengths and positions of said links, and the speed control is automatically kept at a distance from the centre of the record determined by that of the needle on the sound-box. 70

A practical embodiment of the invention is illustrated by the accompanying drawing wherein:—

Fig. 1 is a plan showing a pair of pivoted guide rods or arms, of which the longer is 75 attached to the speed control and the shorter to the tone-arm of a gramophone.

Fig. 2 is an elevation of a speed control with a connection to the pivoted arm.

Figure 3 is an enlarged section of the arm 80 1 or 2 which is preferably made arcuate in cross section for the sake of strength and rigidity.

Figure 4 is a perspective view of the clip 85 5, pivoted to the arm 2 and adapted to grip the tone arm.

Figure 5 is a vertical section through the links 7 and 8, sliding block 11, and guide rod 12.

Figure 6 is a cross section of the perforated pivot pin 4 with arms 1 and 2. 90

Figures 7 and 8 are respectively, an elevation and an underside view of the rod 12 and vertical spindle 14.

Figure 9 is an elevational view partly in 95 section of the supporting post for the guide arms.

Referring to the drawings, a pair of arms 1 and 2 are pivoted at, and radiate from, a common centre at 3, by means of a perforated pivot pin 4, the longer arm 1 having its free end slotted for convenience of adjusting the position of the speed control and the shorter arm 2 being fitted at its free end with a clip 5 pivoted to the arm and adapted to grip the tone-arm 6. A pair of links 7 and 8 are connected to the arms by pins 9 and 10 and are hingedly attached at the point where they meet to a sliding block 11 which is slidable on the rod 12 with the movement of the tone-arm 6, aided by the spring 13 (or other suitable spring) which 100 105 110

surrounds the rod 12 between the pivot 4 and the block 11. One end of the rod 12 is pivoted to the end of the vertical spindle 14 shown in Fig. 9 on which is mounted the 5 perforated pivot pin 4 which carries the arms 1 and 2, and the other end of the rod 12 is supported in a bracket 15 which is fixed to the gramophone cabinet. The spindle 14, as shown in Fig. 9 is mounted pivot- 10 ally at its lower end in a bracket 24 secured to the motor board, and is kept upright by a flat spring 25 which normally bears against its flat lower end. When desired, the spindle 14 can be rocked backward on its pivot 15 to permit rod 12 to be withdrawn from the bracket 15, in which position of the parts the control can be lifted off the machine.

By the arrangement shown the arm 2 and the sound box 16 are uniformly impelled 20 inwardly, i. e., towards the centre of the record 17 by the decreasing diameter of the record track, and this traversing movement of the arm and the sound box is transmitted to, and imitated by, the arm 1 25 connected to the speed control in an equal or in an unequal ratio, according to the respective lengths and positions of the links 7 and 8, and the speed control is automatically kept at a distance from the centre of 30 the record determined by that of the needle on the sound box. Assuming that the links 7 and 8 are equal in length and are respectively connected to the arms 1 and 2, at equal distances from the pivot 4 that the 35 needle is in the groove when the periphery of the record and the contact wheel 18 of the control occupies the groove at the same distance from the centre of the disk but on opposite sides of the centre of the record, the 40 traversing movement of arms 1 and 2 will be equal and coincident at all points, and linear record speed will be constant.

Fig. 2 shows a rolling speed control with a rolling contact wheel 18 connected at 45 to the arm 1, and provided with the worm-wheel 20 driving the governor spindle 21 and weights 22.

It is to be understood that various modifications of the basic idea of the invention 50 may be employed without departing from the scope of the invention.

I claim:—

1. A speed control device for a sound recording and reproducing machine using 55 disk records and having a sound arm, comprising a pair of guide rods pivotally mounted at a common center adjacent the axis of oscillation of the sound arm and adapted to lie at opposite sides of the center of the record, speed control means carried by one 60 guide rod and engageable with the record, the other guide rod being connected to the sound arm, a block slidable along a line dividing the angle between said guide rods, and links pivotally connecting said guide 65 and links pivotally connecting said guide

rods and block whereby movement of the sound arm toward the center of the record causes corresponding movement of the arm carrying the speed control means.

2. A speed controlling device for a sound recording and reproducing machine using 70 disk records and having a sound arm, comprising a pair of guide rods pivotally mounted at a common center adjacent the axis of oscillation of the sound arm and adapted to lie at opposite sides of the center of the record, speed control means carried by a 75 guide rod and engageable with the record, the other guide rod being connected to the sound arm, a slide rod fixedly arranged in a line dividing the angle between said guide rods, a block slidable upon said slide rod, and links pivotally connecting said guide rods and block whereby movement of the sound arm toward the center of the record causes 80 corresponding movement of the arm carrying the speed control means.

3. A speed controlling device for a sound recording and reproducing machine using 85 disk records and having a sound arm, comprising a pair of guide rods pivotally mounted at a common center adjacent the axis of oscillation of the sound arm and adapted to lie at opposite sides of the center of the record, speed control means carried by a 90 guide rod and engageable with the record, the other guide rod being connected to the sound arm, a slide rod fixedly arranged in a line dividing the angle between said guide rods, a block slidable upon said rod, and links pivotally connecting said guide rods and block whereby movement of the sound arm toward the center of the record causes 95 corresponding movement of the arm carrying the speed control means, said links being constructed to provide lost motion at 100 their pivotal connections with said guide rods.

4. A speed controlling device for a sound 105 recording and reproducing machine using disk records and having a sound arm, comprising a pair of guide rods pivotally mounted at a common center adjacent the axis of oscillation of the sound arm and adapted 110 to lie at opposite sides of the center of the record, speed control means carried by a guide rod and engageable with the record, the other guide rod being connected to the sound arm, a slide rod fixedly arranged in 115 a line dividing the angle between said guide rods, a block slidable upon said slide rod, and links pivotally connecting said guide rods and block whereby movement of the sound arm toward the center of the record causing 120 corresponding movement of the arm carrying the speed control means, said links being constructed to provide lost motion at 125 their pivotal connections with said guide rods, and a spring surrounding said slide rod and bearing against said block for as- 130

sisting the convergent movements of said guide rods.

5. A speed control device for a sound recording and reproducing machine using disk records and having a sound arm, comprising a support, a normally upright post pivotally connected to said support arranged adjacent the axis of oscillation of said sound arm, a pair of guide rods pivotally mounted at a common center upon said post and adapted to lie at opposite sides of the center of the record, speed control means carried by one guide rod and engageable with the record, the other guide rod being connected to the sound arm, a slide rod car-

ried by said post and arranged in a line dividing the angle between said guide rod, a keeper normally retaining the free end of said slide rod when the post is in upright position, a block slideable upon said slide rod, links pivotally connecting said guide rods and block, a spring engaging said post for normally maintaining it in upright position, said post being foldable against the tension of said spring to withdraw the free end of said slide rod from said keeper.

In testimony whereof I have signed my name to this specification.

HAROLD ALFRED ROGERS.
